WILLIS S. SHERMAN, OF MILWAUKEE, WISCONSIN.

WORK-POSITIONING MEANS.

1,320,423.

Specification of Letters Patent.

Patented Nov. 4, 1919.

Application filed January 29, 1917. Serial No. 145,123.

To all whom it may concern:

Be it known that I, WILLIS S. SHERMAN, a citizen of the United States, and resident of Milwaukee, in the county of Milwaukee, and State of Wisconsin, have invented new and useful Improvements in Work-Positioning Means, of which the following is a description, reference being had to the accompanying drawings, which are a part of this specification.

This invention relates to the art of end matching and has for its object to provide means which will assure the work being positioned accurately with respect to its line of travel through the machine so that the cutting operation performed thereon will be true or square with the edge and face of the work.

With this object in view the invention provides yielding obstructions in the path of the work accurately positioned to detain the work at one end or the other as it is started in its feeding travel through the machine if such end is in advance of the other, such obstructions being mounted on the pair of parallel pressure bars to be engaged by the work after the latter is under the influence of the pressure bars and exerting equal resistance to the movement over each of the pressure bars irrespective of a possible varying in thickness of the work so that both yield together to permit the work to pass only when the work is at right angles to the line of feed.

The invention also provides means for assuring the work fitting firmly against its upper guide surface before entering the work feeding passageway to render such positioning means effective and, furthermore, provides means for preventing the introduction of work at times when the work positioning means would be ineffective by reason of the pressure bars being held depressed by the preceding work still positioned thereon.

With the above and other objects in view the invention consists in the work positioning means for end matchers as herein claimed and all equivalents.

Referring to the accompanying drawings in which like characters of reference indicate the same parts in different views:

Figure 1 is an end view of a portion of an end matcher showing the receiving end of the work feeding passageway provided

with the work positioning means of this invention;

Fig. 2 is a plan view of the near pressure bar thereof;

Fig. 3 is an enlarged detail view showing the pressure bars receiving irregular work of greater thickness at one end than at the other;

Fig. 4 is a plan view showing the work resting upon both parallel pressure bars;

Fig. 5 is a vertical longitudinal sectional view of a portion of a pressure bar showing the construction and mounting of the yielding work truing means;

Fig. 6 is a transverse sectional view of the plane of line 6—6 of Fig. 5;

Fig. 7 is an end view of one of the pressure bars looking into the receiving end of the work feeding passageway;

Fig. 8 is a sectional view on the plane of line 8—8 of Fig. 1 showing the adjustable pivotal support for the work lifting dog and the slidable holder therefor; and

Fig. 9 is a sectional view on the plane of line 9—9 of Fig. 3 showing the pin connections for the work stopping means connecting it with the stationary support and the pressure bar respectively.

In these drawings 10 indicates the frame of an end matcher on which is supported a head block 11 as usual, forming the upper guide surface for a work feeding passageway leading to cutters 12. Slidably mounted on the frame by means of gib plates 13 are a pair of pressure bars 14 spaced apart and arranged in parallel relation to each other, as shown in Fig. 4 to form the lower bearing surface of the work feeding passageway. The pressure bars 14 are as usual given a tendency to move upwardly with pressure, by means not shown, to a predetermined distance from the head block according to the thickness of the work. Such pressure causes the pressure bars to clamp the work, usually matched flooring, between them and the stationary head block in such manner as to assure the top surface or face of the strips of flooring bearing firmly against the smooth guide surface of the head block as the work is fed through the work feeding passageway by suitable feeding means, reciprocating hook bars 15 working in slots of the head block being shown for this purpose. The feeding of the work through pressure guides in its travel past

100
105
110

cut-off saws and matching cutters is for the purpose of performing the end matching operation accurately at right angles to the parallel matched edges and the plane face 5 of the work. In order to preserve as fixed the angularity of the work with respect to the direction of feed so that it will continue through the machine in the same position in which it is entered in the work feeding 10 passageway, and in order to prevent the work from being forced back from the cutters by the action of the cutters, the pressure bars are provided with upstanding knife edges 16 extending longitudinally of the bearing faces thereof. The knife edges score the bottom of the work and the same score marks fit upon the knife edges of succeeding pressure bars where they operate in tandem. It is of the utmost importance that the work 15 should be accurately positioned with respect to the direction of feed before it engages the knife edges, and while the formation of beveled shoulders 17 on the two parallel pressure bars in a line at right angles to the 20 direction of feed constitutes a means for accurately positioning the work of uniform thickness by abutting the front edge of the work thereagainst on its introduction to the work feeding passageway, such means is not 25 always reliable. In the case of flooring strips which are slightly tapering in thickness from one end toward the other, shoulder 17 of one pressure bar will be engaged earlier than the other, and consequently the 30 two hook bars will not simultaneously force the work against both beveled shoulders to straighten it to a true position if it is not so, and the work may enter the knife edges in a position slightly deflected from the true 35 right angular position, and the end of the work will not be cut square. A supplemental work truing means, operating to again block the travel of the work at points in a line at right angles to the feed and 40 after the work has entered upon the pressure bars and has depressed them more or less according to its relative thickness, is required to overcome the possibility of such defective positioning of the work, such 45 blocking means being carried by the pressure bars themselves so as to be equal in their retarding influence though the pressure bars may be at different elevations owing to the varying thickness of the work. 50

55 The beveled shoulder 17 may be formed directly upon the pressure bar, but as here shown it is formed on the corner of a hard metal block 18 let into the pressure bar at the end of the knife edge 16 and securely 55 held in place by a wedge pin 19. An inverted U-shaped blocking member 20 slidably fits in grooves across the top and along the sides of the block 18 with its two ends resting upon an inverted U-shaped supporting member 21 which passes through an

opening in the pressure bar beneath the block 18 with its ends engaging the opposite sides of the pressure bar. A spring 22 is housed within the pressure bar beneath member 21 and forces it upwardly into engagement with the block 18 to hold the blocking member 20 normally in its raised position. The blocking member 20 has a beveled front edge for the work to bear against and by means thereof it is forced 75 downwardly against the pressure of the spring when the work is forcibly moved over it.

If the work is introduced at an incorrect angle, such as shown in full lines in Fig. 80 4, it will be prevented from entering the work feeding passageway above the pressure bars in that position by the engagement of its advanced portion with one of the shoulders 17. Such advanced portion will be de- 85 tained by the shoulder 17 while the hook bar draws the other end of the work forwardly into engagement with the other shoulder 17. The strip of flooring, when bearing against both shoulders 17, as shown 90 in dotted lines in Fig. 4, is properly positioned in the machine and both hook bars may then pull equally thereon against the same resistance of the shoulders 17 to force both pressure bars downwardly. In this 95 manner the work is trued by the shoulders 17 of the pressure bars when it is of the same thickness or substantially the same thickness at both pressure bars.

When the work is thinner at one point of 100 engagement than at the other, as frequently happens with work that is slightly tapered longitudinally, the thicker edge of the work will engage the inclined surface of the shoulder 17 at a lower point than the 105 thinner edge and consequently the position of the work in which both points first engage such shoulders is not the true feeding position of the work. If such tapering work should approach these shoulders in the true 110 feeding position, it would be thrown out of such position by its thicker end being detained by its earlier engagement with the shoulder 17 while the thinner end moves forwardly. A racking movement of the 115 work feeding means is thus caused by an inequality in the resistances opposed to the two hook bars, and without the supplemental truing shoulders 20 this false position of the work would be maintained in its travel 120 through the machine and the end matching operation would be imperfect.

The supplemental shoulders 20 serve to correct the false position of the tapering work after it has entered upon the pressure 125 bars by opposing equal resistance to both points of engagement of the work. The thinner end of the work, which is in advance as the result of less resistance being offered thereto in overcoming the action of shoulder 130

17, will first engage a shoulder 20 and be detained while the other end of the work is being advanced to correct its position.

The detention of the thinner end of the work by the blocking means 20 will continue until the work is forced along the other pressure bar to the point of engagement with the other blocking means 20 and, as the two blocking means 20 are in a line at right angles to the direction of feed, it will be seen that the end of the work which is in advance is retarded until the other end has been moved up a sufficient distance to bring the work into its proper position at right angles to the direction of feed. At such time both work feeding hook bars 15, which have been restored to their normal positions, act together to force the work over both blocking means 20 and upon the knife edges 20 16 by which it is maintained in its true position throughout the travel through the work feeding passageway.

At its rear edge the blocking member 20 is rabbeted to form a shoulder that will limit the outward movement of the blocking member when it is released by the rear edge of the work passing off of its raised portion. The bearing surfaces of the blocking member 20 may be provided with a supply of 30 lubricant by wicks 23 inserted in openings therethrough.

In order that the retarding and truing shoulders 17 and 20 of the pressure bars may be effective for accurately positioning the work, the pressure bars must be in their extreme upper positions and therefore it is desirable to prevent the introduction of a strip of work until the preceding strip of work has passed beyond the pressure bars. 40 For this purpose a guard member 24 is pivotally mounted on a stationary part 25 such as a lug on the gib plate 13 and is connected with the pressure bar. The guard member 24 is preferably in the form of a leaf spring secured to a block 26 with a pin 27 passing through it and the stationary lug 25 and a pin 28 passing through it and the pressure bar. When the pressure bar is in its uppermost position ready to receive a strip of work, the block 26 is inclined, as shown in Fig. 3, to lower the guard 24 out of the path of the work, but in a lower position of the pressure bar, as when the work is between it and the head block, the guard is raised to the position shown in full lines in Fig. 1, where it intercepts the work if attempt is made to introduce it into the work feeding passageway. As soon as the preceding strip of work passes off of the pressure bar, the guard 24 is lowered out of the path of the work and the work may then enter and in doing so engage and operate a trigger 29 standing in its path to control the operation of the work feeding means and start the machine in another cycle of operation. In or-

der that the spring guard 24 may not be bent out of place by the work striking thereagainst, it is reinforced by engaging an overhanging ledge or shoulder 36 formed by a projection of the block 18, such projection 70 being formed to fit the inclination of the guard member where it bears thereagainst.

It is important that the work should fit closely against the straight guide surface of the head block as it enters the work feeding passageway in order that the detaining and positioning shoulders may be effective and in order that the hook bars may properly engage the rear edge of the work to perform their part in the positioning operation. 80 Each pressure bar is therefore provided with an adjustable spring lifting means for lifting the work against the head block.

The pressure bar has a projection 30 with a screw stud 31 threaded therein and a block 85 32 rests on the projection with a slot in its downwardly extending flange slidably fitting around the screw stud 31 so that the block is clamped in adjustable positions on the projection 30. The block 32 has a slot 90 in the under portion thereof extending to near its upper edge so that there is only a thin piece of metal connecting its front and rear portions and these portions are capable of springing with relation to each other. 95 Within this slot is pivotally mounted a dog 33 with an upturned pointed end for engaging the work and the dog is given a spring action for holding it with pressure in its normal position by means of a coiled spring 100 84 connecting it with an adjustable arm 85 on a screw stud 36 carried by the block. The pivotal support for the dog is specially designed to compensate for the wear of the pointed end thereof, making it possible to 105 elevate the pivotal axis of the dog as the end wears away and thus enable the dog to continue indefinitely its function of forcing the work upwardly against the head block as it is entered in the work feeding passageway. 110 The dog 33 is fulcrumed on a ring 34 which may be bound between the walls of the slot of the block without binding the dog, and a screw stud 35 passes through the front wall of the slot without threaded engagement and is threaded into the rear wall of the slot so that the tightening thereof will cause the walls of the slot to be contracted against the ring 30 and bind it in place. A wide adjustment is formed for the ring by 115 reducing the diameter of the stud 35 where it passes through the ring. When the dog becomes worn and is resharpened its upturned end may be readjusted to its normal elevation by loosening the stud 35 and forcing the dog upwardly to such position. By retightening the stud 35 the dog will be held in this position, its fulcrum ring 34 having been shifted and locked in its adjusted position. With work of different widths the dis- 120 125 130

tance between the point of engagement of the dogs 33 and the detaining and positioning shoulders of the pressure bars should be changed and this is accomplished by adjusting the blocks 32 on the extensions 30 5 of the pressure bars.

In operation the work positioning means of this invention does not interfere with the introduction of work in the proper manner, 10 but prevents the feeding of work when the pressure bars are not in position to receive it. It is not necessary for the attendant to accurately position the strips as he feeds them to the machine, for the dogs 33 first 15 force them into bearing engagement with the head block and then the shoulders 17 or the shoulders 20 cause them to be straightened to a position accurately at right angles to the direction of feed before entering upon 20 the knife edge guides 16. The shoulders formed by the blocking members 20 form substantially equal obstructions to the travel of the work even though the work is tapering in thickness, for they stand the same 25 distance above the bearing surface of the pressure bars and have the same shape and are resisted by approximately the same spring pressure. They thus differ from the shoulders 17 which only oppose the travel 30 of the work to the same degree when the work is of the same thickness at both points of engagement. The importance of equality in the resistance to the travel of the work at both points of engagement of yielding 35 blocking means increases with the ability of the work feeding hook bars to give and take so as to be relatively longer and shorter, a condition which may be incident to lateral play in the slide or other common means on 40 which they are carried. The hook bar structure under such conditions acts as a walking beam and only retains its true position with the hooks at right angles to the direction of feed when the two resistance 45 shoulders in the path of the work oppose the same resistance to its travel. The reliance upon the shoulders 17 alone for positioning the work would be effective only when the work was of the same thickness 50 at both points of engagement with said shoulders, a difference in thickness producing the difference in resistance to unbalance the hook bar structure and throw the work out of true position by moving in advance 55 that portion of the work which is opposed by the minor resistance. The supplemental resistance shoulders 20 correct any such distortion of the feeding means by opposing a second pair of obstructions offering equal 60 resistances at the two points of engagement so that that portion of the work which is in advance of the other will engage the resistance shoulder 20 first and be detained thereby until the other portion is brought 65 up even therewith against the other shoulder

20. The resistance of both shoulders 20 being necessarily equal, irrespective of the thickness of the work, because of their projecting above the pressure bars to the same distance, and because of their spring action 70 being the same, and because of their angle of engagement being the same, the rectified position of the work will be maintained as it travels over the said resistance shoulders 20 and on to the knife edges 16. 75

It is obvious that the invention is not confined to use with the particular form of work feeding means shown as the work positioning means of this invention is equally serviceable with chain feeding 80 means or any other feeding means. It is also obvious that the secondary resistance shoulders need not necessarily be yielding with respect to the pressure bars for they may be rigid therewith and if alike as to 85 shape and size and the spring resistance of the pressure bars is equal as with the use of calibrated springs, the resistance opposed to the travel of the work by such secondary shoulders will be the same though one pressure bar is depressed more than the other because of unequal thickness of the work. It is therefore apparent that the invention is not limited to the details of the construction shown and described and the claims relate to such structural details only when 90 specifically included. It is also obvious that the invention is not confined to its use with end matchers as it may perform the desired functions of positioning the work fed to 100 cut-off saws and various shaping machines, all of which are referred to in the claims as "end matchers and the like."

The diagram illustration in Fig. 4 is not intended to show a work feeding means in 105 a practical form but merely to exaggerate the walking beam tilting effect that may result from slight lateral play of the usual slide or carriage on which the hook bars are mounted. Such lateral play is so slight that 110 it could not be illustrated in the drawing and the give and take of the hook bars whereby one advances ahead of the other is also incapable of illustration so that exaggeration is necessary. The unequal advance of the hook bars may be very slight such as would be incident to the usual play of the slide or carriage on which they are mounted, or the usual play in their pivotal connections, or the aggregate effect of the 115 looseness in fit of the various parts and the end matching operation will be sufficiently out of true as the result thereof to make the present supplemental work positioning means necessary. 120

What I claim as new and desire to secure by Letters Patent is:

1. Means for positioning and feeding work to end matchers and the like, comprising a stationary head block, pressure bars 130

- coöperating therewith to form a work feeding passageway between them, mechanism for forcing the work through the work feeding passageway and a pair of means at distant points in the desired line of position for the work for opposing approximately equal resistances to the travel of the work after the work has depressed the pressure bars to correct the position of the work.
2. A work feeding mechanism for end matchers and the like, comprising a stationary head block, pressure bars forming a work feeding passageway therewith, means for forcing the work through the work feeding passageway, and means on both pressure bars distant from the front ends thereof in the desired line of position of the work to oppose equal resistances to the travel of the work after the work has depressed the pressure bars.
3. A work positioning and feeding mechanism for end matchers and the like, comprising a stationary head block, pressure bars coöperating therewith to form a work feeding passageway therebetween, means for feeding work through the work feeding passageway and resisting shoulders on the pressure bars distant from the front ends thereof and in the desired line of position for the work to equally resist the travel of the work after the work has depressed the pressure bars for truing the work to the predetermined position therefor.
4. A work positioning and feeding means for end matchers and the like, comprising a stationary head block, pressure bars coöperating therewith to form a work feeding passageway therebetween, means for feeding the work through the work feeding passageway and yielding resistance shoulders on the pressure bars distant from their front ends and in the desired line of position for the work to equally resist the travel of the work after the work has depressed the pressure bars.
5. A work positioning and feeding means for end matchers and the like, comprising a head block, pressure bars coöperating therewith to form a work feeding passageway between them, means for feeding work through the work feeding passageway and spring pressed beveled blocking members on the pressure bars at a distance from their front ends and in a line with each other to equally resist the travel of the work after the work has depressed the pressure bars.
6. A work positioning and feeding means for end matchers and the like, comprising a head block, pressure bars coöperating therewith to form a work feeding passageway between them, means for forcing work through the work feeding passageway, blocks removably inserted in the pressure bars, an inverted U-shaped blocking member slidably mounted in grooves of each block,

an inverted U-shaped supporting member passing through an opening in the pressure bar with its ends engaging the opposite sides of the pressure bar and having the ends of the blocking member bear thereon, 70 and a spring seated within the pressure bar and bearing on the supporting member.

7. In a work positioning means for end matchers and the like, a supplemental stop, comprising a spring pressed blocking member having a beveled front edge and a rabbeted rear edge whereby the blocking member is depressed by the pressure of the work against its beveled front edge and is limited in its outward movement by the engagement 80 of the shoulder of its rabbet with the rear edge of the work as the work passes therefrom.

8. A work positioning and feeding means for end matchers and the like, comprising a head block, pressure bars coöperating therewith to form a work feeding passageway between them, means for feeding the work through the work feeding passageway, work resisting means on the pressure bars for 90 truing the work and means dependent upon the depression of the pressure bars by the presence of work thereon for preventing the introduction of work to the work feeding passageway. 95

9. In a work positioning and feeding means for end matchers and the like, a stationary support, a pressure bar movable thereon and forming a guide surface for a work feeding passageway and a guard member having pivotal connection with the stationary support and with the pressure bar respectively to be moved by the movements of the pressure bar into position for preventing the insertion of work in the work 100 feeding passageway while the pressure bar is depressed by the presence of work thereon.

10. A work feeding means for end matchers and the like, comprising a head block, a pressure bar coöperating therewith to form 110 a work feeding passageway therebetween, means for feeding the work through the work feeding passageway, and means for positioning the work against the head block before it enters the work feeding passageway, comprising a dog pivotally mounted on the pressure bar with a pointed end engaging the work and means for holding the dog against the work with pressure.

11. In a work feeding means for end 120 matchers and the like, comprising a head block, a pressure bar coöperating therewith to form a work feeding passageway therebetween and means for positioning the work against the head block before it enters the 125 work feeding passageway comprising a block adjustably mounted on the pressure bar and having a slot extending nearly therethrough, a spring actuated dog passing through the slot, a ring on which the dog is 130

6
fulcrumed, said ring being of greater width than the dog and engaging the walls of the slot, and means for pinching the walls of the slot together to hold the ring in adjusted positions.

12. In a work feeding means for end matchers and the like, a head block, a pressure bar coöperating therewith to form a work feeding passageway therebetween, means for feeding work through the work feeding passageway and means for holding work against the head block before it enters the work feeding passageway, comprising a block adjustably mounted on the pressure bar and having a slot extending nearly therethrough, a dog passing through the slot, a ring on which the dog is fulcrumed, said ring being of greater width than the dog and engaging the walls of the slot, a screw 10 stud passing through the block and the ring for clamping the walls of the slot against the ring for holding the ring in adjusted position, said screw stud being reduced in diameter to permit of the adjustment of the 15 ring, an adjustable arm on the block and a spring connecting the adjustable arm with the dog.

13. A work positioning and feeding means for end matchers and the like, comprising a head block, pressure bars coöperating therewith to form a work feeding passageway therebetween, means for feeding the work through the work feeding passageway, supplemental work resisting shoulders on the pressure bars distant from their front ends 30 to impose equal resistance to the travel of the work after the work has depressed the pressure bars, guard members having connection with the pressure bars and with a stationary support for preventing the introduction of work to the work feeding passageway while the pressure bars are depressed by the presence of work thereon and means for positioning the work against the head block before it enters the work feeding 35 passageway comprising a spring pressed dog adjustably mounted on the pressure bar.

40 In testimony whereof, I affix my signature, in presence of a witness.

45 WILLIS S. SHERMAN.
